UNITED STATES PATENT OFFICE.

WILL W. WILLARD, OF SAGINAW, MICHIGAN.

RAILROAD-TIE.

1,130,455.

Specification of Letters Patent.

Patented Mar. 2, 1915.

Application filed December 11, 1913. Serial No. 805,993.

To all whom it may concern:

Be it known that I, WILL W. WILLARD, a citizen of the United States of America, residing at 200 Benjamin street, Saginaw, 5 W. S., in the county of Saginaw and State of Michigan, have invented certain new and useful Improvements in Railroad-Ties, of which the following is a specification.

This invention relates to the subject of 10 railroad ties, and the primary object of the same is to produce a composite tie in which the body portion is formed of plastic material and the rail-engaging portion is formed of metal.

15 The invention contemplates the production of ties in which the body is formed of material that can be readily shaped and hardened to withstand all shocks and jars incidental to rail traffic and which will not 20 be affected by atmospheric changes, and which is provided with seats for rail engaging members, so that said members will be rigidly, but readily detachably, connect- 25 ed therewith.

25 In addition, the invention contemplates the production of novel rail engaging members that coöperate with the body to form firm supports and fastenings for the rails.

In carrying out the invention as generally stated above, it will be apparent that 30 the same is susceptible to changes in details and structural arrangements, one simple and practical embodiment being shown in the accompanying drawings, wherein—

35 Figure 1 is a perspective view of the improved tie. Fig. 2 is a perspective view of one of the sections, or blocks, of the tie, the rail-engaging members being removed. Fig. 3 is a perspective view of the rail members 40 of the tie, the rail clamps being omitted. Fig. 4 is a view in perspective showing a transverse section of one of the blocks. Fig. 5 is a fragmentary longitudinal sectional view through the upper portion of one of 45 the blocks, showing a rail fastened thereon. Fig. 6 is a perspective view of one of the rail clamps.

The improved railroad tie comprises a pair of blocks or sections, one for each rail,

the blocks being designated by the numeral 50 1 and being duplicates. These blocks are preferably formed of a composition including clay mixed with sand and gravel, the composition being pressed or otherwise formed into the desired shape, and then subjected to heat to bake them to the necessary 55 degree of hardness. These blocks can also be made of cement.

Each block 1 has a centrally located, longitudinally extending groove 2 formed in 60 its upper surface. The upper portion of the groove 2 is wider than the lower portion, the arrangement being such that seating ledges 3 are formed at the sides and ends of said groove. Side seats 4 extend 65 transversely from the longitudinal centers of the side ledges 3, the seats 4 being in the nature of wide grooves that extend to the longitudinal edges of the top surface of the block 1 and have continuations 5 that extend down the sides of said block. An opening 6, having its ends located in the seats 5, extends transversely through the block 1. The block 1 is also provided with a pair of parallel longitudinal openings 7 which extend through or partly through said block 70 and intersect the opening 6, the openings 7 having their entrance ends at the inner end of the blocks. The sides of the block may be provided with grooves 8, so that the block 80 may be readily grasped with tongs to facilitate handling. Wide, shallow grooves or panels 9, having beveled sides and ends 10, are formed in the bottom of the block 1 to cause the block to interlock with the road- 85 bed.

The rail-engaging members of the tie comprise a plate 11, which may be a casting that is of a size to snugly fit on the ledges 3 over the groove 2, the plate having 90 centrally located lateral flanges 12 that fit the seats 4 and from which the side wings 13 depend and fit in the seats 5. On each side of its transverse center, the plate 11 is provided with a longitudinal slot 14 that 95 is preferably narrower than, and registers with, groove 2 of the block 1, the outer end of each slot 14 terminating in an enlarged,

and preferably rectangular head 15. Just beyond the heads 15, upstanding abutment lugs 16 extend transversely across the end portions of plate 11. The side flanges 13 are provided with openings 17 that register with openings 6 in the block 1, and through said openings 6 and 17 an insulated sleeve or bushing 18 extends. A bolt 19 extends through the sleeve 18, and by means of the end nut 20, the bolt 19 rigidly, but detachably holds the plate 11 to its seat in the block 1.

As is clearly shown in Figs. 1 and 4, the plate 11 through the side flanges 12, forms a flat bearing surface that extends transversely across the center of the tie, and such bearing surface provides a seat for the base of the rail A. The rail A is held to its seat by means of the flat plates 21 having their free ends reduced to provide lips 22 that overlap and clamp upon the upper surfaces of the rail flanges. Rearward movement of the clamps 21 is prevented by the abutment lugs 16, as is shown in Figs. 1 and 5 of the accompanying drawings. The clamps 21 are held in rail-gripping positions by means of the bolts 23 that project upward through the slots 14, said slots being narrower than the heads of said bolts. The bolts 23 extend through openings 24 in the clamps, and nuts 25 lock the bolts in position to firmly fasten the clamps to the plate 11 and rail flange. To remove the clamps 21, the nuts 25 are removed from the bolts, whereupon the said clamps may be readily lifted from the plate 11. To remove the bolts 23, they are moved through the slots 14 until the heads 15 of said slots are reached, whereupon the bolts may be readily lifted from the plate 11. A reversal of the described movement of the bolts 23 permits bolts to be readily replaced.

As is clearly shown in Fig. 1 of the accompanying drawings, each complete tie includes two duplicate sections, one for each rail, and such sections are rigidly connected by the bars 26 that enter the openings 7 of the blocks 1. The bars 26, adjacent their ends, are provided with transverse openings 27, (see Fig. 4 of the drawings) and the sleeves 18 and bolts 19 extend through said openings 27. By this manner of connecting the two sections, it will be seen that by removing one bolt 19 and one sleeve 18, the sections may be disconnected, thereby permitting the removal of one section for replacement, repairs, &c., when necessary or desirable, without disturbing the other section.

As is clearly shown in Fig. 4 of the drawings, the sleeves 18 effectively insulate the fasteners 19 from the flanges 13 and the bars 26, so that in the event of the rails or one of the rails, being used for signaling purposes,

short circuiting through the fasteners and said bars is prevented.

It will be observed that the seats 4 and 5 formed in the block 1 are of such depth that the outer surfaces of the flanges 12 and wings 13 are flush with the surfaces of the sides and top of said block. Another advantage of the use of the flat flush seats for the rails is that the rails can be readily adjusted laterally to compensate for wear on the sides of the heads of the rails. For example, the members of the sets of clamps 21 may differ in length, and as they are interchangeable, it will be apparent that by shifting said members and adjusting them through the medium of the bolts 23 and slots 15 and 2, the rails will be bodily moved laterally, such adjustments being obviously facilitated by the fact that the upper surface of the tie is perfectly flat. In addition, the described manner of fastening the rails to the plate 11, permits the insertion of blocks or other rail-elevating devices between the rails and their seats when necessary or desirable.

What I claim as my invention is:

1. A railroad tie comprising a block having a longitudinal groove in its upper surface, said groove being surrounded by seating ledges, said upper surface having transversely extending side seats, and the body having seats on its sides that communicate with the transverse seats, a plate seated on the ledges and having side flanges and wings that enter the transverse and side seats, said plate having slots that communicate with the groove, rail fasteners having bolts that extend through the groove and slots, and means for fastening the plate to the body.

2. A railroad tie comprising a block having a top groove, a plate seated on the block, and having side flanges and wings that overlap the sides of the block, said plate having longitudinal slots terminating at their outer ends in enlarged heads, said plate having end abutment lugs, fastening bolts removable through said heads of the slots, said bolts normally having their heads in the grooves and their shanks projecting through the slots, rail clamps carried by the bolts, and means engaging the flanges for fastening the plate to the block.

3. A rail tie comprising a block having its upper surface provided with a central, longitudinal groove, said groove having its ends and sides provided with seating ledges, said upper surface having central transverse seats that communicate with the groove and the sides of the block having central vertical seats therein which are continuations of the upper seats, a rail plate seated on the ledges of the groove and having side flanges and wings that fit within the upper and side seats of the block, the center of the

plate including the flanges forming a flat seat for a rail that extends across the upper surface of the block, said plate having transversely extending abutments adjacent its ends and having longitudinal slots adjacent the abutments, rail clamps engaging the abutments, fasteners engaging the clamps and extending through the slots of the plate,

and means for fastening the plate to the block.

In testimony whereof I have affixed my signature in presence of two witnesses.

WILL W. WILLARD.
